FLOOR RACK FOR TRANSPORTATION UNITS

Harry K. Blanning, Chicago, Ill., assignor, by
mesne assignments, to International Steel Com-
pany, Evansville, Ind., a corporation of Indiana

Application December 30, 1948, Serial No. 150,441

Term of patent 14 years

(Cl. D14—6)

To all whom it may concern:

Be it known that I, Harry K. Blanning, a citizen of the United States, residing at 8329 Langley Avenue, Chicago, in the county of Cook and State of Illinois, have invented a new, original, and ornamental Design for a Floor Rack for Transportation Units, of which the following is a specification, reference being had to the accompanying drawing, forming part thereof.

Fig. 1 is a perspective view of the floor rack for transportation units, illustrating the floor rack raised in vertical position; Fig. 2 is a perspective view of the floor rack when lowered to horizontal position; and Fig. 3 is a perspective view of one of the transverse sections of the floor rack of my invention illustrating my design.

I claim:

The ornamental design for a floor rack for transportation units, as shown.

HARRY K. BLANNING.
